RAILWAY TRAFFIC CONTROLLING
APPARATUS

Ronald A. McCann, Swissvale, Pa., assignor to The
Union Switch & Signal Company, Swissvale,
Pa., a corporation of Pennsylvania

Application August 13, 1940, Serial No. 352,379

4 Claims. (Cl. 246—219)

My invention relates to railway traffic controlling apparatus, and it has particular reference to the organization of such apparatus into railway traffic controlling systems of the class wherein 5 the operation of a railway traffic controlling device, such as a railway track switch, is controlled by a control member located at a remote point.

My invention relates to improvements in railway traffic controlling apparatus of the type described and claimed in a copending application for Letters Patent, Serial No. 352,098 filed by John M. Pelikan on August 10, 1940.

It has been proposed heretofore to control 10 the operation of a traffic controlling device from a remote point by means of a polarized control relay connected in a control circuit supplied with current of one relative polarity or the other in accordance with the position of a control member located at the remote point. Such proposed systems incorporate traffic locking for the polarized control circuit and also incorporate storage preventing means so arranged that if the control member is moved while the locking 15 is effective, the storage preventing means becomes effective to prevent the polarized control circuit from being conditioned to cause the control relay to assume a position of correspondence with the control member either at the time of movement of the member or subsequently when the locking is released, thereby requiring that the control member be in a position of correspondence with the device and the locking be ineffective in order to enable a movement of the control member to obtain the desired operation of the controlling device.

Remote control systems of the above described class incorporating means for preventing storage of control of the traffic controlling device in the event that the control member is operated when the locking is effective, generally require that the control member be operated from one position to the other within the slow release period of a relay which when released functions to prevent storage of the control of the device, that is, it removes the polarized control relay from control by the control member if the locking is effective when the control member is moved to a position out of correspondence with the controlling device. When it is desired to employ as the control member an ordinary acting control lever of the three-position type having contacts closed in one or the other of two extreme positions but open at the mid or neutral position intermediate the two extreme positions, this time

limitation within which the control member must be moved is at times undesirable and an accidental hesitation in the mid position of the lever, or a very slow lever movement by an operator, might enable the slow release relay to 5 release and thereby prevent the controlling device from being controlled to its desired position when the lever finally is moved to the new position. This loss of control resulting from release of the storage preventing relay when the 10 lever is moved too slowly, has substantially the same effect upon the operation of the device as if the locking were effective, and hence it might cause the operator to become confused and conclude that the traffic locking is effective whereas 15 in fact the loss of control is the result of unnecessarily slow lever movement.

In view of the above-mentioned and other important considerations, it is an object of my present invention to provide a novel and improved control system of the above described class wherein the apparatus is so arranged that a slow operation of the control member will not cause loss of control of the railway traffic controlling device. 20

Another object of my invention is to incorporate into a remote control system of the above described class, means for preventing storage of control without necessitating movement of the 25 control member to be completed within a limited time.

An additional object of my invention is to provide a novel and improved system for controlling a railway traffic controlling device from a remote point in such manner as to prevent 30 storage of control of the device, and wherein control of the device is established through the medium of a manually operable control member of the ordinary acting type having contacts which are selectively closed in one or the other 35 of two extreme positions and which contacts are open when a lever is in a mid or neutral position intermediate the two extreme positions of the lever.

A further object of my invention is to provide a novel and improved system for controlling a railway traffic controlling device by a control member located at a remote point. 40

The above-mentioned and other important objects and characteristic features of my invention 45 which will become readily apparent from the following description, are obtained in accordance with my invention by reversibly energizing a polarized switch control relay over a control circuit governed by two repeater relays, one for 50 55

the control member and the other for the controlling device. These repeater relays are of the two-position type adapted when deenergized to remain in their last operated position, and these 5 relays cooperate to control another or storage preventing relay in such manner that the other relay and the polarized control relay are energized if the locking is ineffective when the two repeater relays occupy corresponding relative 10 positions, and the polarized control relay is caused to operate from one position to the other over a control circuit which includes a front or stick contact of the storage preventing relay.

I shall describe one form of apparatus embodying my invention, and shall then point out 15 the novel features thereof in claims.

The accompanying drawing is a diagrammatic view illustrating a preferred form of apparatus embodying my invention.

20 Referring to the drawing, the reference character TS designates a railway traffic controlling device which is adapted to be moved between a normal position and a reverse position by means of suitable operating mechanism controlled from 25 a remote point. As herein shown, device TS is a railway track switch which connects the rails of a main track X to the rails of a diverging track Y. The operation of switch TS is effected by means of a suitable switch operating mechanism SM which may, for example, be an electric or 30 electropneumatic switch machine. Switch mechanism SM is controlled by suitable control means such, for example, as by a polarized relay WR which in turn is controlled from a remote 35 point in a manner to be explained shortly, and it is believed sufficient to state that when relay WR is energized by current of one relative polarity to close its front contact 4 and its normal polar contact 5—6, switch mechanism SM is controlled 40 to operate the switch to its normal position as illustrated in the drawing, and when relay WR is energized by current of the opposite relative polarity to close its front contact 4 and its reverse polar contact 5—7, the switch mechanism 45 is controlled to operate switch TS to its reverse position.

The reference character J designates a circuit controller operatively connected with switch TS. Circuit controller J comprises movable contact 50 members 8 and 9 which occupy normal positions, as shown in the drawing, when the switch is in its normal position, and which contact members are operated by the switch to reverse positions when the switch occupies its reverse position. Circuit 55 controlling contacts 10 and 11 are engaged by members 8 and 9, respectively, to form contacts 8—10 and 9—11 in the normal position of the members, while in the reverse position of the members contacts 12 and 13 are engaged by 60 members 8 and 9, respectively, to form contacts 8—12 and 9—13.

The reference character 1TR designates a detector locking relay comprising a track relay connected in a track circuit provided for the section 65 of track including switch TS. The reference characters 2LLSR and 2RLSR designate approach locking relays arranged to release when a train approaches the detector track section, and which relays are controlled by circuits which 70 form no part of my present invention but which may, for example, be similar to the circuits shown provided for approach locking relays U¹ and U² in Letters Patent of the United States No. 1,929,047, granted on October 3, 1933, to Earl M. 75 Allen and Charles A. Brooks, for Remote control

apparatus. The reference character V designates a control member comprising a manually operable lever having a normal position N and a reverse position R. Lever V may, for example, be a non-interlocked switch lever of an interlocking machine positioned at a point remote from switch TS; and it is provided with contacts selectively closed in accordance with the position of the lever. Each contact of lever V bears a reference character N or R, indicating the position of the lever in which such contact is closed. For example, contact 15 of lever V bears a reference character N to indicate that this contact is closed when the lever is in its extreme normal position, while contact 16 of the lever bears a 10 reference character R to indicate that the latter contact is closed when the lever occupies its extreme reverse position. Both contacts 15 and 16 are open when lever V is moved to its mid or neutral position intermediate its normal and reverse positions. Lever V functions, in a manner to be explained in detail presently, to control the supply of current of one relative polarity or the other to a polarized control circuit provided for switch control relay WR, provided that 20 traffic conditions adjacent switch TS are favorable for permitting operation of the switch.

A two-position relay WA of the type, such as, for example, the magnetic stick type, characterized by the fact that the relay remains in its 30 last operated position when deenergized, is provided to repeat the position of lever V. As shown, relay WA is a two-winding relay effective when its normal winding is energized to operate its polar contact members to their normal or left-hand positions, as viewed in the drawing, and effective when its other or reverse winding is energized to operate its polar contact members to their reverse or right-hand positions. One winding of relay WA is energized over an obvious 40 circuit passing from lower terminal 17, as viewed in the drawing, of battery SB through contact 15 of lever V, the right-hand terminal of relay WA, the normal winding of relay WA, and the mid terminal of relay WA to center terminal 18 45 of the battery. When the lever is in its reverse position, a circuit is completed for relay WA passing from terminal 17 through lever contact 16, left-hand terminal of relay WA, and the other or reverse winding of relay WA and mid 50 terminal of relay WA to center terminal 18 of the battery.

The reference character WPR designates a switch repeating relay controlled by circuit controller J to repeat the position of switch TS. 55 Relay WPR also is of the type which remains in its last operated position when deenergized, and in the normal position of switch TS, relay WPR is energized by current of what I shall term normal polarity over an obvious circuit including 60 contacts 8—10 and 9—11 of controller J, and relay WPR accordingly operates its polar contact member 21 to its normal or left-hand position, as viewed in the drawing, wherein normal polar contact 21—22 is closed. In the reverse position of switch TS, contacts 9—13 and 8—12 of circuit controller J are closed to pole change the current supplied to relay WPR, and as a result 65 relay WPR is energized by current of reverse polarity and operates its polar contact member 21 to its reverse or right-hand position wherein reverse polar contact 21—23 is closed.

A locking or storage preventing relay LPR also is provided to prevent storage of control of the switch in the event that lever V is moved during 75

the interval that operation of the switch is unsafe due to traffic conditions adjacent the switch. Locking relay LPR is sufficiently slow releasing to bridge the interval required for the polar contact members of relays WA and WPR to operate from one position to the other.

Having thus described the apparatus embodying my invention, I shall explain the manner in which it operates and shall at the same time 10 trace the circuits over which the various parts of the apparatus are controlled.

In the normal condition of the apparatus as represented in the drawing, lever V, repeater relay WA, control relay WR, switch repeating relay 15 WPR and switch TS occupy corresponding normal positions. The detector and approach locking relays 1TR, 2LLSR and 2RLSR also are energized and are in their ineffective or inactive locking positions with the result that the previously 20 mentioned control circuit for relay WR is completed and relays WR and LPR are supplied with current of normal polarity over a normal control circuit which extends from terminal 17 of battery SB through normal polar contact 25-26 of relay 25 WA, the winding of relay LPR, normal polar contact 27-28 of relay WA, normal polar contact 21-22 of relay WPR, front contacts 29, 30 and 31 of relays 2LLSR, 2RLSR and 1TR, respectively, and the winding of relay WR to mid-tap 30 terminal 18 of battery SB.

With the apparatus in its normal condition, the switch may be controlled to its reverse position by reversing lever V. When the switch control lever is moved out of its normal position, contact 15 of the lever opens to open the energizing circuit of relay WA, but relay WA retains its polar contact members in their normal or last operated positions, as pointed out previously, so that if the lever is held in its mid position wherein both normal and reverse contacts 40 15 and 16 are open, contacts 25-26 and 27-28 of relay WA continue to complete the previously traced normal circuit of relays WR and LPR, and as a result such relays are maintained energized.

When lever V is moved into its reverse position wherein contact 16 is closed, the reverse winding of relay WA is supplied with current over its previously traced reverse circuit and relay 50 WA accordingly is caused to operate its polar contact members to their reverse positions. In this condition of the apparatus, relay WR is supplied with current of the opposite relative polarity over a reverse control circuit which extends from mid terminal 18 of battery SB through the winding of relay WR, front contacts 31, 30 and 29 of relays 1TR, 2RLSR and 2LLSR, respectively, normal polar contact 21-22 of relay WPR, front contact 36 of relay LPR, reverse polar contact 35-34 of relay WA, the winding of relay 55 LPR, and reverse polar contact 33-32 of relay WA to terminal 19 of battery SB. The reversal of current polarity in the circuit of relay WR of course causes that relay to operate to its reverse position and thereby control switch machine SM to operate the switch to its reverse position.

The movement of switch TS from its normal position actuates controller J to open contacts 70 8-10 and 9-11 and thereby open the previously mentioned normal energizing circuit of relay WPR, but relay WPR retains its polar contact member 21 in its last operated normal position, as pointed out previously, to retain closed the reverse operating circuit of relay WR so that as a

result relays WR and LPR are retained energized. When the switch is operated to its full reverse position and controller J closes its reverse contacts 8-12 and 9-13, relay WPR is energized by current of reverse polarity and accordingly operates its polar contact member 21 to its reverse position to close reverse polar contact 21-23 and complete a reverse circuit for relay WR which differs from the previously traced reverse control circuit of relay WR only in that reverse 10 polar contact 21-23 of relay WPR replaces front contact 36 of relay LPR and normal polar contact 21-22 of relay WPR.

With lever V, repeater relay WA, control relay WR, switch TS and switch repeater relay WPR 15 in corresponding reverse positions, as assumed above, the switch may be operated back to its normal position by restoring lever V to its normal position. The operation of the apparatus when lever V is restored to its normal position 20 is believed to be obvious from an inspection of the drawing taken in connection with the foregoing description of the operation of the switch from its normal to its reverse position, and further detailed description is believed to be un- 25 necessary.

From the foregoing, it can be seen that relay WR is reversibly energized over a circuit controlled by control lever V in such manner that the circuit means remains energized during the 30 interval that the lever is being moved from one extreme position to the other. It follows, therefore, that there is no limitation placed upon the time within which the lever must be moved in order to retain control of the switch control 35 relay, but rather the lever may be moved as slowly as it is desired.

In the event that the apparatus is in its normal condition, as shown, and the train approaches the switch to release approach locking relay 40 2LLSR or 2RLSR, or if the train occupies the section including the switch so that relay 1TR releases, the previously traced control circuit of relay WR is opened and relays WR and LPR become released. Under such assumed conditions, if the operator moves lever V to its reverse position, the locking provided by the approach and/or detector locking relays prevents operation of the switch at this time and also conditions the apparatus so that when the locking 50 subsequently becomes ineffective, control of the switch is restored to the operator only after the lever is restored to its position of correspondence with the switch. This protection against the storage of control of the switch is effected 55 upon movement of the lever when the locking is effective, due to the fact that if relay LPR is released when relay WA follows the movement of the lever and assumes a position out of correspondence with the switch as indicated by relay WPR, the circuit over which relay WR is caused to operate when the relays WA and WPR are out of correspondence and which circuit includes front contact 36 of relay LPR, can- 60 not be completed when the locking becomes ineffective. It follows, therefore, that after the locking becomes ineffective, relays LPR and WR remain deenergized until such time as the lever is restored to its position of correspondence with 70 relay WPR, and when that happens the previously traced normal energizing circuit of relay WR is completed and relays LPR and WR become reenergized.

With relays LPR and WR energized, the operator may operate the switch 75

to its reverse position by setting lever V into its reverse position, as pointed out previously.

It is obvious that if the switch and control lever are in correspondingly reverse positions, 5 the movement of the lever when the locking is effective conditions the apparatus to remove relay WR from control of the lever after the locking becomes ineffective, unless the lever is restored to its reverse position in correspondence 10 with the position of the switch. When this is done the apparatus is then conditioned to enable the operator to control the switch to its normal position by setting the lever in its normal position.

15 From the foregoing description, it is evident that apparatus embodying my invention provides means for controlling a traffic controlling device from a remote point in such manner that storage of control is prevented by means which is independent of the time of operation of the remote control lever. It follows, therefore, that the operator cannot lose control of the device due to a slow lever movement so that if a lever movement is not effective to cause the operation of 20 the device, the operator is assured that such operation is not prevented because of a slow lever movement, thereby decreasing the possibility of confusion regarding the cause of the loss of control of the device.

30 Although I have herein shown and described only one form of railway traffic controlling apparatus embodying my invention, it is understood that various changes and modifications may be made therein within the scope of the appended 35 claims without departing from the spirit and scope of my invention.

Having thus described my invention, what I claim is:

40 1. In combination, a manually operable control member for controlling a polarized control relay into correspondence with the member, a railway traffic controlling device controlled into correspondence with said control relay, lock means rendered active or inactive in accordance with traffic conditions adjacent the device, a first two-position magnetic stick relay reversibly operated into correspondence with said control member, a second two-position magnetic stick relay reversibly operated into correspondence with said device, and means controlled by said two two-position relays for reversibly energizing said control relay over a circuit which may be closed when said lock means is inactive and which if closed remains closed when said member is moved 45 intermediate its control positions, said last mentioned means including storage preventing means controlled by said lock means and active, after said lock means becomes inactive, to prevent operation of said control relay into correspondence with said member if said member is out of correspondence with said device when said lock means becomes inactive.

60 2. In combination, a manually operable control member for controlling a polarized control relay to a position of correspondence with the member, lock means effective when active to lock

said control relay against operation, a railway traffic controlling device controlled to a position of correspondence with said control relay, a first two-position magnetic stick relay controlled to a position of correspondence with said device, a 5 second two-position magnetic stick relay controlled to a position of correspondence with said member, and circuit means controlled by said two magnetic stick relays for reversibly operating said polarized control relay in response to a movement of said member to a position out of correspondence with said device if and only if said lock means is inactive at the time of movement of the member.

65 3. In combination, a manually operable control member for controlling a polarized control relay to a position of correspondence with the member, lock means effective when active to lock said control relay against operation, a railway traffic controlling device controlled to a position of correspondence with said control relay, a first two-position magnetic stick relay controlled to a position of correspondence with said device, a second two-position magnetic stick relay controlled to a position of correspondence 10 with said member, another relay, circuit means including the winding of said other relay and effective when said two magnetic stick relays are in corresponding relative positions when said lock means is inactive for normally energizing 15 said polarized control relay, and circuit means including a front contact of said other relay and effective when said second magnetic stick relay is caused to operate to a position out of correspondence with said first magnetic stick relay 20 when said lock means is inactive for operating said polarized control relay to a position of correspondence 25 with said control member.

4. In combination with a railway traffic controlling device, a polarized relay for controlling 40 the operation of said device, a contact responsive to traffic conditions adjacent said device and closed only when conditions are favorable for operation of said device, two relays each of the two-position type that remains in its last operated position when deenergized, means controlled by said device for operating a first of said two-position relays to a corresponding position, a two-position manually operable control member for operating the second of said two-position relays to a position of correspondence, another relay, a circuit including the winding of said other relay and said traffic controlled contact for normally energizing said polarized relay with current of normal or reverse polarity according as 45 said two two-position relays occupy corresponding relative normal or reverse positions, and another circuit including a front contact of said other relay and said traffic controlled contact for energizing said polarized relay with current of 50 normal or reverse polarity according as said second two-position relay is caused by an operation of said manually operable member to operate to its normal or reverse position out of correspondence with said first two-position relay. 55 60 65
